Primary Examiner — Freda S Nunn(74) *Attorney, Agent, or Firm* — Oppedahl Patent Law Firm LLC**CLAIM**

The ornamental design for a multimode display device, as shown and described.

DESCRIPTION

FIG. 1 is a front view of the new design for a multimode display device;

FIG. 2 is a top view of FIG. 1;

FIG. 3 is a perspective of FIG. 1;

FIG. 4 is a front view of the new design for a multimode display device in another mode;

FIG. 5 is a bottom view of FIG. 4; and,

FIG. 6 is a perspective view of FIG. 4.

The features shown in broken lines in the drawings depict environmental subject matter and form no part of the claimed design.
